[57] CLAIM

The ornamental design for a pivotal segment, as shown and described.

DESCRIPTION

FIG. 1 is a partial sectional view of a pivotal segment showing my new design, the broken line showing the two attached interconnected pivotal segments is for illustrative purposes only and forms no part of the claimed design;

FIG. 2 is a perspective view thereof;

FIG. 3 is a top plan view thereof;

FIG. 4 is a partial sectional view thereof taken along the line 4—4 in FIG. 3;

FIG. 5 is an exploded view of the connector portion, shown separately for illustrative purpose only;

FIG. 6 is a right side elevational view thereof the left

side elevational view being a mirror image;

FIG. 7 is a front elevational view thereof;

FIG. 8 is a bottom plan view thereof;

FIG. 9 is a right side elevational view of a second modified embodiment of the design shown in FIGS. 1-8; and,

FIG. 10 is a bottom plan view thereof.

FIG. 1

FIG. 2

FIG. 3

FIG. 4

FIG. 5
